INVENTOR:
ROBERT HENRY COLLEN
by his Attorneys
Howson and Howson

UNITED STATES PATENT OFFICE.

ROBERT HENRY COLLEN, OF EAST HAM, ENGLAND, ASSIGNOR OF ONE-HALF TO JOHN BROADWOOD & SONS LIMITED, OF LONDON COUNTY, ENGLAND, A BRITISH COMPANY.

DRAWER-LIFTING SUPPORT.

Application filed August 7, 1924, Serial No. 730,648, and in Great Britain July 7, 1924.

My invention relates to articles requiring to be withdrawn, or opened, and returned to place, or closed, by sliding movement in such manner as to prevent jamming, or 5 working stiffly in the housings in which they slide, said articles being of the type in which an extensible arm of the kind known as "lazy tongs" is employed at the side, or at both 10 sides of the article, the present invention being more especially intended for application to drawers which are滑den into, and from, a chest in which they are housed and, in describing my invention, I will presume that it is so applied, from which its application 15 to analogous articles (such for instance as the specimen cases of cabinets) will also be understood.

According to my invention there is connected to the forward part of the drawer, 20 (and usually, for ease of movement at each side of the drawer) one end of the extensible arm, the other end of which is engaged within the housing in the chest with a guide, which will impart an upward tilt to the forward end of the said arm, so as to lift, or 25 tend to lift the drawer as it is withdrawn and relieve it from the friction, or some of the friction, incidental to its sliding movement from, and into, the chest.

30 I will describe, with reference to the accompanying drawing, a construction in accordance with my invention.

Figures 1 and 2 are both side elevations partly in section one shewing the drawer 35 closed and the other shewing the drawer opened.

At each side of the drawer A is an extensible arm consisting of a system of links b connected together, at their mid-parts and 40 at each end by pins in the manner of the devices known as "lazy-tongs," the foremost c^2 of the pins C being mounted in a plate d secured to the forward part of each side of the drawer, whilst the rearmost and the 45 third of the pins (those marked respectively c^3 and c^4) are capable of sliding in, or on, guides secured inside the chest B and of such inclination as to somewhat tilt the forward end of the said lazy-tongs arm when 50 the drawer is being opened. The said guides are preferably slots, f, f^2 in line with each

other, in a plate g, secured to the inside of the chest-housing for the drawer, in line with the centre-pin attachment (c^2) to the forward part of the drawer A. The centre-pin c^5 , between the rearmost pin c^3 and the third pin c^4 of the lazy-tongs arm, is mounted in the aforesaid plate g inside the chest so that this pin c^5 constitutes a longitudinally fixed centre between the two slots 60 f , f^2 upon which centre the lazy-tongs arm turns sufficiently as the aforesaid rearmost and third centre-pins c^3 and c^4 move along their respective slots f^2 and f to give the aforesaid lifting, or tilting, movement to 65 the drawer A. The sides of the drawer are sufficiently recessed, or set inwards, to accommodate the lazy-tongs arms and their connections and the upper edges of the said sides are sufficiently reduced in height (as 70 shewn at a) to allow of the said lifting, or tilting, movement. It is understood that there are also similar devices at the other side of the drawer A. When the drawer A is shut, or slid, into the chest B, the lazy- 75 tongs arms will collapse, as shewn in Figure 2, and the drawer A takes up the closed position upon its supports in the chest B as the rearmost and third centre-pins c^3 and c^4 move toward the pin c^5 in their respective 80 slots f^2 , f in the plate g secured to the inside of the chest B.

In the following claims it is to be understood that "drawer" includes also analogous 85 slideable objects, lazy-tongs arm includes also 85 any suitable extensible and retractable device of an analogous character and "chest" covers also any equivalent housing into, and from, which the drawer, or other object, slides.

What I claim is:—

1. For use with drawers and analogous slideable articles housed in a chest, having a lazy tongs arm providing a support for the slideable article, pins connecting the elements of the lazy tongs arm, in combination with a guide having two slots mounted in a side wall of the chest, an intermediate one of said pins being fixed in said guide between the two slots, and another of said pins on each side of said intermediate pin sliding in a slot.

2. For use with drawers and analogous slideable articles housed in a chest, having a lazy tongs arm providing a support for the slideable article, pins connecting the elements of the lazy tongs arm, in combination with a guide having two slots mounted in a side wall of the chest, the second of said pins

from one end of the lazy tongs arm being fixed in said guide between the two slots, and the first and third of said pins sliding ¹⁰ in the two slots, substantially as described.

In testimony whereof I have signed my name to this specification.

ROBERT HENRY COLLEN.
